Primary Examiner — Mitchell I. Siegel*(74) Attorney, Agent, or Firm* — Randy K. Chang(57) **CLAIM**

The ornamental design for a golf club head, as shown and described.

DESCRIPTION

FIG. 1 is a perspective sole bottom view of my new design for a golf club head;

FIG. 2 is a front view thereof;

FIG. 3 is a sole view thereof;

FIG. 4 is a top view thereof;

FIG. 5 is a back view thereof;

FIG. 6 is a toe view thereof; and,

FIG. 7 is a heel view thereof.

The broken line showing is included for the purpose of illustrating portions of the golf club head that form no part of the claimed design. The dash-dot broken lines represents the boundary and form no part of the claimed design.

1 Claim, 4 Drawing Sheets(56)
